FLUID-SUPPLY APPARATUS

Application filed September 8, 1924. Serial No. 736,414.

The invention in its broader aspects pertains to the supply of two or more fluids such as air and gas to form a combustible mixture at the point of consumption.

The primary aim of the invention is to provide for the supply of a plurality of gaseous fluids in varying volumes as desired for consumption, and in a desired ratio, with a higher degree of efficiency than has heretofore been possible.

10 In the supply of air and gas for purposes of combustion, the more common method in use involves the premixing of the air and gas in proportions such that a secondary air supply must be admitted at the burners.

15 This method is objectionable because of its inefficiency due among other things to the necessity for manual adjustments which necessarily render the operation and the control uncertain, and to different physical 20 characteristics of the gases variously affecting their flow under varying conditions so as to render their accurate control at the point of introduction to the mixing apparatus practically impossible.

25 Another method, less frequently employed, consists in forming a complete combustible or explosive mixture in a compressor and delivering this mixture through a pipe system to the burners. This method not only 30 involves uncertainty in proportioning the air and gas constituting the mixture due to their different physical characteristics, but involves also a dangerous fire hazard because of the explosive character of the mixture which in practice necessitates a minimum 35 velocity slightly greater than the rate of flame propagation to prevent backfiring. This method, because of the accompanying fire hazard is generally limited to use where 40 the volume consumed is relatively small.

With the difficulties attending prior methods in view, as set forth briefly above, the object of my invention is to produce a method of and apparatus for supplying air 45 and gas for combustion, wherein the air and gas are admitted to the apparatus in the proper ratio to insure efficient combustion, and are separately delivered in varying volumes as desired to the combustion zone and 50 without any attending fire hazard.

In carrying out my invention I provide positively actuated impellers of suitable construction for each of the fluids to be supplied. These impellers are operated at a uniform speed, preferably by a single power unit, and each operates upon its respective 55 fluid separately and is arranged to deliver such fluid independently to the combustion zone. The respective impellers are made of capacities such as to deliver their fluids in the proper ratio, and to insure uniformity 60 of operation, the pressures of the fluids at the inlets of the various impeller casings are stabilized and preferably brought to the same level, as for example, atmospheric pressure. In the preferred form, I control the 65 volume delivered solely by regulating the speed of the driving unit, which is an electric motor having control means adapted to effect a wide range of speeds. The arrangement is such that the function of the two 70 impellers acting respectively on the air and gas is that of propelling them through their respective discharge pipes at a velocity sufficient only to supply the consumption demand. The gases therefore flow under a relatively 75 low pressure so that the loss due to friction is small. In prior apparatus where a secondary air supply is admitted at the burner, the gases are necessarily under a high state of compression due in the first 80 place to the necessity for maintaining a velocity sufficient to overcome the rate of flame propagation, and in the second place to the fact that a high velocity of the gases is required to induce the flow of sufficient volume 85 of secondary air supplied at the burner to support combustion and to cool the burner so as to prevent pre-ignition from the heat of the burner. It is well known that the friction of a gas flowing through a passage 90 increases substantially with the pressure, and it will thus be apparent that where the gases are separately delivered to the point of consumption under low pressure as in my invention a substantial saving in power is 95 obtained.

Another important advantage of this apparatus resides in its commercial possibilities. Thus I contemplate that the apparatus may be constructed in the form of small units 100

requiring a driving motor of only a fraction of a horse power and consuming very little current, it being only necessary for the impellers to operate on the several gases sufficiently to effect their propulsion toward the point of combustion in a sufficiently large volume to supply the fuel requirements at that point.

A further advantage consists in the fact that the flow of each of the gases is under definite control so as to be supplied in exactly the proper ratio.

Still another advantage residing in my invention is that it is capable of economical construction because of its extreme simplicity. It therefore is available to small consumers of gas where the cost of the large systems now in common use is prohibitive.

Finally, the use of a plurality of separate small units in a large industrial plant as compared with a single system supplying all of the outlets results in a substantial saving in power because only such of the burners as are in actual use at a given time require an expenditure of power, whereas in the case of the large systems in common use compressors are employed to place the gases under a high state of compression and operate at maximum capacity at all times irrespective of the number of burners in use.

In the accompanying drawings I have illustrated a preferred embodiment of my invention, but I contemplate that various changes in construction and arrangement will occur to those skilled in the art without departing from the spirit and scope of the invention as expressed in the appended claims. I also contemplate that the invention is susceptible to general application not limited to the supply of air and gas for combustion purposes.

In the drawings Figure 1 is a view partially diagrammatic in character illustrating an air-gas supply system embodying my invention, the major portion of the apparatus being shown in section.

Fig. 2 is a sectional view taken approximately in the plane of line 2—2 of Fig. 1.

Fig. 3 is a similar view in the plane of line 3—3 of Fig. 1.

Fig. 4 is a plan view of the air and gas discharge pipes, with the end portions thereof shown in section to illustrate a minor feature of construction.

Fig. 5 is a vertical sectional view through the parts shown in Fig. 4 and taken on line 5—5.

Fig. 6 is a general view illustrating a modified form of the invention.

Fig. 7 is a fragmentary plan view illustrating a different form of means for varying the speed of the impellers.

Referring first to Figs. 1 to 5, I have in this instance shown two impellers constructed as a unit but operating respectively upon separate fluids which for convenience I will here-

inafter refer to as "air" and "gas." 8 designates generally the air impeller and 9 the gas impeller. The former has a casing 10 of the snail type with a central inlet opening 11 and a tangential outlet opening or discharge port 12. The latter or gas impeller has a snail type casing 13 with a central inlet opening 14 and a tangential outlet opening or discharge port 15. The two casings 10 and 13 are in this instance placed side by side to form a single structure with the inlet openings 11 and 14 disposed on opposite sides of the structure. The respective casings have inwardly extending flanges 16 and 16^a suitably secured together leaving a central opening which is closed by means of a plate or disc 17 forming part of the two impellers as will presently be described. The disc 17 thus constitutes a partition wall between and common to the two casings. Its peripheral edge in the present instance operates between the outer wall of gas casing 13 and its flange 16^a. An annular ring 18 fast upon the disc 17 is bent to overlie the flange 16 in order to cut off communication between the two casings while permitting of the rotation of the disc relative to the casings.

The two impellers are also unitary in construction. That for the air comprises a series of blades 19 curved at their outer ends as shown in Fig. 3. These blades are rigidly secured at one side edge to the disc 17. Similarly the impeller for the gas comprises curved blades 20 rigidly secured to the opposite side of the disc 17. At its center, the disc 17 is made fast upon a shaft 21 of an electric motor 22 suitably supported so that its shaft is disposed concentrically of the two casings. 23 designates generally a rheostat of common construction for controlling the supply of current to the motor 22 whereby to vary the speed of operation of the pressure unit. This device is preferably of the type so constructed that in the event of a failure of the current supply the operating lever will return to its starting point so that a manual operation is required to set the apparatus in motion upon a resumption of the current supply.

It is preferable that the gas be admitted to the casing 13 at a pressure equal to the pressure of the air admitted to the casing 10, to-wit, atmospheric. To this end I employ an automatic pressure governor 24 in the gas supply line 25, which is connected with the inlet opening 14 of the casing 13. This governor comprises a casing 26 having a diaphragm 27 therein to the upper side of which atmospheric pressure is admitted through a port 28. The diaphragm 27 has secured thereto a valve member 29 operating to control the flow of gas through a port 30 in a diagonal wall 31 formed in a depending wall 32 of the casing. The diaphragm is weighted as shown at 33 and 34 so that nor-

mally the valve member 27 tends to open the port 30 the weights 33 and 34 being sufficient to balance the pressure of the incoming gas against a flexible wall 35 secured between the main section 26 of the casing and the depending valve housing 32. The weights being balanced, the valve is operated by atmospheric pressure upon the upper side of the diaphragm 27. A building up of pressure ahead of the governor 24 is communicated to the under side of the diaphragm through a port 36, and the arrangement is such that when this built up pressure equalizes or balances the atmospheric pressure upon the upper side of the diaphragm, the valve 29 will be closed by gas main pressure acting upon the under side of the diaphragm 35, thus shutting off the further supply of gas until the pressure in the pipe line ahead of the governor falls.

It may sometimes happen that when the apparatus is inoperative the pressure in the pipe line between the governor and the impeller may be less than atmospheric; and inasmuch as atmospheric pressure on the under side of the diaphragm 27 is necessary to effect a closing of the valve I have provided means controlled by the propelling means to insure that the pressure in the pipe line ahead of the governor shall not be less than atmospheric and hence insure the closing of the valve when the operation of the apparatus ceases. This means comprises an ancillary valve casing 37 located in the pipe line 25 between the governor and the impeller casing 13. Said casing 37 has a valve 38 therein for controlling the flow of gas through the pipe line. A diaphragm 39 in a depending portion 40 of the casing forms a pressure chamber 41 which communicates by way of a pipe 42 with the air casing 10 at a point adjacent its outlet opening. 43 is a port establishing communication between the pipe line leading to the casing 13 and the chamber 41^a formed on the upper side of the diaphragm 39. When the apparatus is shut down suction ceases in pipe line 25 and chamber 41^a, at the same time pressure ceases in line 42 and chamber 41, diaphragms 44 and 39^a are then unsupported in their raised positions and fall with the attached gravity weight 44 closing the connected ancillary valve 38 which is locked in its closed position by gas main pressure which may accumulate in the chamber above diaphragm 39^a subsequent to the closing of the ancillary valve 38. Conversely when the apparatus is in operation, the suction in the pipe line 25, induced by the gas impeller, combined with the pressure produced by the air impeller upon the under side of the diaphragm, opens the valve 38 so as to render the governor 24 operative to stabilize the gas in the supply line at atmospheric pressure.

It will be observed that by the construc-

tion provided the air and gas are confined during their passage through their respective casings, and this relation is maintained until the gases reach the point of combustion. Thus I provide separate discharge pipes or conduits 45 and 46 for the air and gas, respectively, leading to the combustion zone within a furnace chamber 47, the pipes being herein shown as arranged concentric at their discharge ends and communicating with the combustion zone through a port 48 in the wall of the furnace. The concentric relation of the two pipes at their discharge ends is clearly shown in Figs. 4 and 5. The pipe 46 being of smaller diameter than the pipe 45, enters the latter at a point near its discharge end, and from thence the two pipes are merged to form the concentrically arranged discharge passages 49 and 50.

To insure an intermixture and commingling of the two gases I provide in the respective passages 49 and 50 spirally arranged blades 51 and 52 (Figs. 4 and 5), two such blades being shown in each passage. Moreover the blades in the respective passages are oppositely inclined so as to produce whirling motions of the two gases in opposite directions.

It is an essential feature of the mechanical structure provided that the air and the gas be confined within separate noncommunicating compartments during their passage through the apparatus, as shown herein the air compartment is made up of the air impeller casing 10 and the discharge pipe 45 which is connected to the outlet of the casing 10, the gas compartment is made up of the gas main 25, on which the gas governor casing 24 and the gas valve casing 37 are mounted and by which they are connected to the inlet of the gas impeller casing 13, and the gas discharge pipe 46 which is connected to the outlet of the casing 13; this construction provides for the safe operation of the apparatus by preventing any mixing of air and gas within the apparatus and thus effectually removes the hazard of a gaseous mixture fire or explosion within the apparatus.

Summarizing the operation of the apparatus shown in Figs. 1 to 5, the motor 22 is set in motion by the operation of the rheostat 23 at a speed determined by the volume of the two gases which are required for combustion. The two impellers are thus driven as a unit and air and gas are drawn into the respective inlet openings 11 and 14 in a fixed ratio determined by the proportions of the parts in each instance and by the physical characteristics. The gas is supplied to its impeller at a pressure equal to the air due to the functioning of the governor 24. The latter receives gas at a fluctuating pressure from the supply main and operates in a well known manner to maintain a pressure in the supply line equal to the atmospheric pressure on the upper side of the diaphragm 27.

When the operation of the apparatus commences, the suction induced in the gas line 25 is transmitted to the upper side of the diaphragm 39, and pressure near the outlet port 12 of the casing 10 is transmitted to the under side of the diaphragm 39, with the result that the valve member 38 is instantly and positively operated to open the passageway through the pipe line. Conversely when the impellers cease their operation, the suction on the upper side of the diaphragm 39 is interrupted as is also the pressure on the under side of the diaphragm, so that the action of the weight 44 plus the pressure of the gas upon the upper side of the small diaphragm 39 quickly and positively moves the valve member 38 into closed position. As a result, pressure behind the valve 38 builds up and is transmitted to the under side of the diaphragm 27 overcoming the pressure upon the upper side thereof and closing the valve 29.

The gases discharged from the two casings 10 and 13 are conducted by their respective pipes 45 and 46 to the combustion zone, the two pipes merging into a concentric relation at this point, and because of the presence of the oppositely inclined blades 51 and 52 in the discharge pipes 49 and 50, whirling motions are imparted to the two gases in opposite directions, thus effecting their intimate mixing and commingling.

It will be observed that the two impellers operate positively to propel the respective gases in measured flow through their respective discharge pipes to the combustion zone. The ratio, being determined by the proportion of the parts, and the fixed physical characteristics of the gases, is always definite and certain. There is no opportunity for pre-combustion, because the gases are separately confined. Further, there is no necessity for imparting to the gases a velocity greater than that necessary to supply the combustion needs. There is thus no waste of the gas, and there is no necessity for high compression, nor for the provision of cooling equipment made necessary by the generation of excessive heat. Further, because the gases are separately confined up to the point of combustion, it is not necessary to admit a secondary air supply at the burner to cool the parts and prevent pre-combustion as is the case where the two gases are premixed and confined within a single pipe. An important factor is the saving in the power, it being apparent that by avoiding high compression and by eliminating waste a saving in current consumption by the motor is effected.

There is thus a total absence of the usual attending fire hazard, and at the same time the operation is carried on with maximum efficiency.

An important factor is the simplicity of the structure as compared to prior appara-

tus. No control valves, either at the inlet openings or at the point of discharge are employed which reduces the cost of manufacture, and also renders it unnecessary to employ skilled attendants.

In the embodiment shown in Fig. 6, the two impellers 8' and 9' are made separately, but both are driven from a common drive shaft 21' of a motor 22' located between the two impellers. The fluids are discharged into pipes 45' and 46', which merge into a concentric relation, as in the embodiment above described and shown in Figs. 1 to 5.

In some instances it may be desired to provide for a variation in the ratio of the two gases, as for example when it is desirable for different classes of work to vary the carbon content of the combustible mixture. I have in this embodiment of my invention shown the two casings equipped with sleeves 53 and 54 arranged axially thereof and adjustable in and out to vary the respective capacities of the two impellers as may be desired.

In Fig. 7 I have shown a means for controlling the speed of operation of the fans in place of the rheostat 23. This means comprises a friction disc 55 fast on the shaft 21" and a friction pinion 56 having a slideable but non-rotatable connection with the shaft of the driving motor 57. The pinion 56 is arranged to be adjusted relative to the disc 55 and held in adjusted position by means of a clamp 58 coacting with a rod 59 of a frame 60 in which the motor shaft and the shaft 21" are journaled. This type of control may be preferred to the rheostat control in cases where the apparatus is called upon to supply a large volume of mixture as for example in blast furnaces, a constant speed motor being preferable where the load is heavy.

I claim as my invention:

1. The combination of a pair of impellers operating upon separate fluids to discharge them at a common point to effect a mixture of the two fluids, and means for driving each of the impellers at a speed determined by the volume of mixture which it is desired to supply, the ratio of the two fluids in the mixture being determined by the relative capacities of the two impellers, and means for varying said relative capacities.

2. The combination of a pair of casings, having separated inlet ports and discharge ports communicating at a common point, a shaft mounted in said casings and having a disc thereon rotatable in the casings and constituting a division wall therebetween, and blades on opposite sides of said disc constituting impellers for the respective casings for moving separately measured volumes of gases to said common point for combustion.

3. An air and gas supply apparatus comprising a pair of casings each having an inlet and an outlet opening, said inlet openings communicating respectively with separate

sources of gas supply, an impeller for each casing, an electric motor for driving said impellers as a unit, a pair of discharge pipes leading from said outlet openings respectively and discharging at a common point, and a rheostat for controlling the speed of operation of the motor whereby to vary the volumes of the gases supplied to said point, the ratio of the two gases being predetermined by the relative capacities of the two impellers.

4. The combination with a source of gas supply, of a supply pipe, means including an impeller for delivering said gas in varying volumes from said supply pipe to a combustion zone, a governor operating to stabilize the pressure of gas supply including a valve means controlled by the pressure of the gas in the supply pipe at the governor outlet arranged to operate said valve, and means controlled by said impeller to increase the pressure in the supply pipe when the impeller is idle whereby to hold the governor valve closed.

5. The combination with a pipe line communicating with a source of gas supply and impelling means having an air inlet, an inlet communicating with said pipe line and an outlet communicating with a combustion zone, of a governor for stabilizing the pressure of the gas supplied to the impelling means and including a valve adapted to open when the pressure in the pipe line at the governor outlet falls below atmospheric pressure, and means for closing said valve when the operation of the compressor is interrupted comprising a second valve in the pipe line between the governor and the impelling means, and a pressure element acting to open said second valve only when the impelling means is in operation, said pressure element being subject on one side to the suction of the impelling means and on its other side to the pressure at the discharge side of the impelling means.

6. The combination of a disk having impeller blades for handling air and gas in separate compartments of a compressor having each compartment having an inlet and an outlet and a pipe line communicating with a source of gas supply and the gas inlet of the compressor with a governor for stabilizing the pressure of the gas supplied to the compressor and including a valve adapted to open when the pressure at the governor outlet falls to atmospheric pressure and means for closing said valve when the operation of the compressor is interrupted comprising a second valve in the pipe line between the governor and the gas impeller, and a pressure element acting to open said second valve only when the compressor is in operation, said pressure element being subject on one side to the suction of the gas impeller and on its other side to the pressure at the air outlet of the compressor.

7. The combination with a pipe line com-

municating with a source of gas supply, an air impelling means having an air inlet, a gas impelling means, an inlet communicating with said pipe line and gas impelling means and an outlet communicating with a combustion zone, of a governor for stabilizing the pressure of the gas supplied to the gas impelling means, said governor comprising a diaphragm controlled valve seated when the gas impelling means is at rest and means whereby upon starting of both of the impelling means a suction will be applied to one side of the governor valve diaphragm and a pressure on the other, thereby causing the valve to open.

8. The combination with a pipe line communicating with a source of gas supply, a gas impeller whereby a suction is created in the pipe line, a valve casing carried by said pipe line, a valve in said casing and cooperating with a valve seat, said valve being carried by a diaphragm in the casing having a chamber on opposite sides thereof, means whereby upon starting of the impeller a suction will be created in the chamber above the diaphragm and means whereby a simultaneous pressure will be created in the chamber below the diaphragm, thereby unseating the valve.

9. The combination with a pipe line communicating with a source of gas supply, a gas impeller whereby a suction is created in the pipe line, an air impeller, a valve casing carried by said pipe line, a valve in said casing and cooperating with a valve seat, said valve being carried by a diaphragm in the casing and having a chamber on opposite sides of said diaphragm, a casing for said air impeller, a pipe connection between said casing and the valve casing and discharging into the chamber thereof below the diaphragm and forming means whereby upon operation of the air impeller pressure is applied below the diaphragm, said gas impeller forming means whereby a suction will be applied in the chamber above the diaphragm thereby unseating the valve.

10. In a fluid supply apparatus, the combination of a pair of casings each having a central inlet and a peripheral outlet, said inlets communicating with separate sources of fluid supply, an impeller wheel in each casing, vanes on each impeller proportioned to circulate the said fluids through the said casings between the said inlets and outlets at a desired volume ratio, with fluid pressure governor means, communicating with the inlet of one of the said casings, activated when the said impeller wheels are active and suppressed when they are inactive to control the pressure of one of the said fluids.

11. In a fluid supply apparatus, as described herein, in combination, a pair of compartments through the apparatus, each compartment having a suction inlet at a point of fluid supply and a discharge outlet at a com-

bustion zone, in one of the said compartments a gas supply pipe carrying automatic gas pressure stabilizing means a casing inclosing a fluid impeller and having a discharge pipe terminating at the said combustion zone, in the second of the said compartments a second casing inclosing a second fluid impeller and having a second discharge pipe terminating at the said combustion zone, an electric motor having a driving shaft extending through the said casings and carrying the said impellers, a rheostat controlling the said motor for driving the said impellers at a variable speed, vanes on each of the said impellers proportioned to circulate the said fluids at a desired volume ratio through the said compartments, with deflecting means placed directly in the said discharge outlets to impart oppositely whirling directions to the said fluids as they issue from the said outlets.

12. In a fluid supply apparatus, in combination, with a pair of casings each having an inlet and an outlet and a positively driven fluid impeller wheel, one of the said casings having a source of fluid supply at its inlet and a discharge pipe at its outlet vented at a combustion zone, the second of the said casings having a fluid supply pipe at its inlet and a second discharge pipe at its outlet vented at the said combustion zone, of deflecting means directly in the outlets of the said discharge pipes to cause opposite whirling motions in outflowing fluids.

13. In a fluid supply apparatus in combination, a pair of casings having inlets at separate sources of gas supply and separate outlets at a common combustion zone, gas flow directing means at the said outlets, an axial driving shaft in the said casings; and proportional impeller means separately mounted on the said driving shaft in the said casings for co-operate actions upon the said gases thereby to maintain a predetermined volume ratio, and by differential impeller pressure means to control the flow of a gas in one of the said casings.

14. In a fluid supply apparatus as described herein, the combination, of a compartment having a gas inlet pressure governor, an automatic gas governor flow control, a ratio gas volume impeller, and a discharge gas flow deflector; with a second compartment having a ratio air volume impeller, a pressure tube communicating with the said gas governor flow control, and a discharge air flow deflector for united deflector actions to mix the said gas and air for burning, beyond their discharge point, in a common combustion zone.

15. A means for independently delivering a number of gases at a common combustion zone, comprising, in combination, compartments each having an inlet and an outlet for a gas, rotative gas impelling members with compensating vanes to provide a desired vol-

ume ratio and diameters to provide desired pressures in the delivered gases, gas mingling discharge members, and on one of the said compartments an inlet gas pressure equalizer member and a member controlling the operation of the said equalizer.

16. The method of separately conveying ratioed supplies of air and of a formulated fuel gas to a common combustion zone, which consists, in moving a volume of air and a volume of gas, controlling the gas pressure to equalize it, applying differential pressure to operate the gas flow control, regulating the flow volumes and pressures, and discharging from separate outlets at a common combustion zone the air and gas volumes for mixing and burning.

17. The method of effecting the complete combustion of a formulated fuel gas, as described herein, which consists, in circulating the said gas through a closed compartment by rotative means formulated to act on the said gas to move it, at a predetermined volume rate per revolution and at a desired pressure increase, to discharge it at a combustion zone there to intimately mingle the said gas with an air volume circulated through a second closed compartment by rotative means proportioned to act on the said air to move it, at a predetermined volume rate per rotation and at a desired pressure increase, to discharge it at the said combustion zone there to mingle with the said gas to form a ratioed mixture proportioned to effect the complete combustion of the aforesaid formulated fuel gas.

In testimony whereof, I have hereunto affixed my signature.
